MEANS FOR HEAT-TREATING MATERIAL

Henry A. Drefein, West Chicago, Ill.

Application September 25, 1947, Serial No. 776,090

4 Claims. (Cl. 263—36)

1

This invention relates to improvements in means for and methods of heat-treating material such as metal and has for an object annealing, normalizing or malleableizing of metal in the form of strips, sheets, or the like, and castings.

Heretofore, in the normalizing of cold rolled strip, for example, it has been the practice in certain "batch" methods to encase the coiled strip in a species of single or double walled retort and to apply heat either to the exterior of said retort or between the walls. This is expensive and requires considerable time. In another practice, electrical means has been utilized for direct heating, but this, too, is generally quite expensive. Also, endeavors have been made to utilize indirect heating means by burning gas in appropriately arranged tubes to render them radiant. In this last process, the heat to which such tubes must necessarily be subjected to obtain the desired heating of the strip or sheets is sooner or later destructive of the tubes. In still another practice, for example, as described in my Patent No. 2,233,474, dated March 4, 1941, the strip or sheet has been directly heated in a heating zone by burning a rich fuel gas mixture therein after having been indirectly heated in a preheating zone, where the partially burned gases from the heating zone are burned in radiant tubes.

My presently disclosed process entirely eliminates the use of such indirect heating in radiant tubes and thereby avoids combustion problems inherent in burning fuel mixtures inside tubes, avoids the expensive periodic replacement of such tubes, and at the same time avoids the deleterious corrosive effects on the strip itself which previously were considered unfavorable in the burning of fuel gas in direct contact with the metal being heated.

In my present process, I first preheat the cold rolled strip as it is fed through a preheating chamber, after being uncoiled and flattened. It is next passed through a main heating chamber to which is supplied partially burned fuel gas abnormally rich in gas content so as to create a reducing atmosphere to preclude oxidation or tarnishing of the strip, while at the same time, effectively and rapidly bringing it to the desired temperature and maintaining that temperature for the period of time requisite to effect the desired normalizing. After that, the strip is cooled by passage through one or more chambers for that purpose. A portion of the partially burned gases from the heating zone is induced into the preheating zone by a stream of additional air and is further combusted therein to directly preheat the

2

strip. The hot gases from the preheater are passed in heat exchange with the stream of additional air entering the preheater zone to improve the overall heat efficiency of the process. Another portion of the partially burned gases from the heating zone is diverted into the cooling chamber to maintain a controlled, non-oxidizing atmosphere therein.

Another object consists in the utilization of a generally similar process, except as to temperature ranges, to sheets or other metal articles for annealing the same.

Another object is the provision of a novel burner arrangement for the preheating chamber wherein air, preheated by exchange with the preheating chamber combustion products, is utilized to aspirate or induce partially burned fuel gases from the heating chamber into the preheating chamber for additional combustion therein with the preheated air.

Another object is the provision of a novel, uniformly-cooled strip-supporting roller which will remain undistorted, even under wide variations of operating conditions, including prolonged work stoppages during which the top of the roller may be subjected to relatively greater heat than the bottom, causing it to warp. This improved cooling permits the use of ordinary steel rollers instead of the relatively expensive alloy rollers conventionally employed for this purpose.

Another object in connection with the cooled roller is the provision of a heat deflecting member surrounding a substantial portion thereof, to increase overall efficiency of the apparatus by minimizing wasteful heat transfer from the heated chambers to the relatively cold roller.

These other objects will be more fully explained in the following specification and illustrated in the accompanying drawings in which:

40 Figure 1 is a vertical longitudinal section through a portion of an improved apparatus illustrating one embodiment of my invention and showing the preheating chamber and the parts associated therewith;

45 Fig. 1a is a similar section of a continuation of the portion shown in Fig. 1, showing the main heating chamber and parts associated therewith;

Fig. 1b is a similar section of the remaining portion of the apparatus showing the cooling chamber and the parts associated therewith;

Fig. 2 is an enlarged sectional view of one embodiment of the internally-cooled roller forming part of the present invention;

Fig. 2a is a sectional view of Fig. 2 taken along the line 2a—2a;

3

Fig. 3 is a vertical transverse section of the preheating chamber taken along the line 3-3 of Fig. 1;

Fig. 4 is a vertical transverse section of the heating chamber taken along the line 4-4 of Fig. 1a;

Fig. 5 is a fragmentary enlarged view of either Figs. 1 or 1a showing one form of the aspirating or Venturi means employed for inducing rich gases from the heating chamber into the preheating chamber;

Fig. 5a is a sectional view of Fig. 5 taken along the line 5a-5a; and

Fig. 6 is a vertical transverse view of the heat exchanger portion of the apparatus shown in Fig. 1 and is taken along the line 6-6.

My apparatus generally is constructed in the usual manner of refractory materials, properly reinforced and supported, such details forming no specific part of my invention other than as they enter into the general combination.

In the illustration, at the charging end, designated by numeral 21, is provided a wall 22 having an outlet opening 23 for material such as a strip 24 of steel being heat-treated, the opening 23 being closable to any extent desired by a fire brick door 26 suspended by chain 27 from the counter-weighted lever 28. The strip or sheet 24 is adapted to be fed continuously through the apparatus, there being a series of transverse, spaced, intermediate rollers or rolls 29, rotated at such speed as to make their peripheral, linear velocity identical with the feeding rate, so that the metal of the strip will not be marred or scratched. The rolls 29 situated at hot locations in the apparatus will be cooled internally in accordance with a portion of the invention to be described subsequently herein. It will be understood that the cold rolled strip, if originally supplied coiled, will be unrolled and flattened before delivery to the apparatus. At the discharge end 31 is provided a pair of pinch rolls, as they are termed, designated by numeral 32. The object of the pinch rolls is to make the smallest possible furnace opening to minimize the escape of furnace gases therethrough. They also assist in effecting the movement of the metal by gripping it and drawing it through the furnace. All of the rolls, for convenience, may be driven by a common drive chain 33 and sprockets 34, one of the latter being provided for each of the intermediate and feeding rollers, as illustrated diagrammatically in Fig. 1b, for example. The chain 33 is provided with a takeup device, generally designated 36, including a vertical loop in the chain and a floating sprocket 37 supporting weights 38. At the rear end of the chain 33 a double sprocket 34a is provided, having one portion for supporting the chain 33 and another portion for supporting the drive chain 39, the latter being connected to one portion of another sprocket 41, the other portion of sprocket 41 driving a chain 42 which turns the lower one of the pinch rolls 32. The sprocket 41 is rotatably driven through beveled gearing 43 and shaft 44 by a combined electrical motor and speed reducer F, diagrammatically illustrated in Fig. 1b.

At the charging end of the furnace is provided what I term a preheating chamber A. Extending from the rear end of that is the main heating chamber B; there being a bridge wall or partition 46 between the two chambers. At the opposite end of the main heating chamber is a cooling chamber C which may comprise a single chamber such as illustrated in Fig. 1b, or where desired,

4

it may comprise a number of successively disposed cooling cells, for example as disclosed in my previous Patent No. 2,233,414, above mentioned.

Along the sides of the main heating chamber B are provided a series of burners generally designated 47, which as shown in Fig. 4, are connected to gas and air supply lines 48 and 49 controlled by valves 48a and 49a, respectively. Each burner is disposed to discharge into a ceramic throat member 51 and is set back therefrom suitably to permit the entrance of secondary air.

A combined Venturi or aspirating means and secondary burner means, generally designated 52, is provided to transfer to the preheating zone and complete the combustion of a portion of the rich, partially burned gases which will exist in the heating zone. This means is best shown in Fig. 5 and comprises a pressure regain tube 53 set in the separating wall 46 and a jet member 54, also having a low pressure area 56 therebetween which is defined by the spacing between the separating wall 46 and the upright outside wall 57 of the heating chamber B. One or more sets of aspirating elements 53-54 may be provided, depending on their size and on the combustion requirements in the preheating chamber A. Each of the jet members 54 is sealed tightly in the wall 57 to prevent the induction of secondary air from the outside in what has previously been the conventional manner, thereby providing that the secondary air required to complete burning of the rich gases transferred from chamber B to chamber A will be supplied only by the jet members 54. As best shown in Fig. 3, the means 52, illustrated, employs 3 sets of the above-mentioned aspirating elements 53-54. Each of the jet members 54 is provided with a plurality (in this case 6) of circularly arranged discharge openings 58 communicating through conduit 59 and control valve 61 with the manifold 62 which is supplied with air through the main supply line 63. Each of the jet members 54 is likewise provided with a central discharge opening 64 which is in communication through conduit 66 and control valve 67 with the air supply manifold 62. Thus, it will be seen, that the air supplied through discharge opening 64 is controllable independently of air supplied through the other discharge opening 58. This arrangement permits a very fine, vernier-like adjustment and close control of the air needed for a sustaining combustion in the preheating chamber A. The main valve 61, controlling the discharge through the six openings 58 of each jet member, may be adjusted to provide the approximate amount of air required and the valve 67 controlling the air through opening 64 may be adjusted to supply the exact amount of air required.

The rich, partially burned gas which is drawn from the heating chamber B into the low pressure space 56 will be at a higher temperature than the minimum required for its ignition and, consequently, upon mixing with the air issuing from the jets 54, it will be instantly ignited and its combustion completed in the preheating chamber A.

In addition, this arrangement provides a convenient way of increasing the induction from the heating chamber without increasing the air supply through pipe 63. By shutting off the center opening 64 or by throttling it in a suitable amount, the air in pipe 63 will be forced at a higher pressure through the remaining openings 58. This increases the velocity of the air pass-

ing into the throat member 53 thereby increasing the amount of gas induced from the heating chamber by lowering the pressure at 56. This assists gas in leaving the furnace yet avoids the objectionable high furnace pressures that otherwise would have to be employed for this purpose. The top of the preheating chamber A, forwardly of the tube 53, is enlarged to provide a secondary combustion zone 68 therein. At the forward end of the preheating chamber A, as best shown in Fig. 1, is in this instance provided an outlet port 69 connected by a flue or duct 71 into a heat exchanger 72. The conduit 22 is illustrative of only one of many means, which will occur to one skilled in the art, of conveying the burned gases from the preheating chamber A to the preheater 72. In another means (not shown) which may be preferred in some instances the hot gasses will be drawn out of the forward opening 23 beneath the door 26 and thence conveyed to the preheater 72. The latter is provided with a series of air tubes 73 and gases burned in the preheating chamber are drawn upwardly through the preheater 72, around the tubes 73, and into the duct 74 which is connected into an exhaust stack or chimney (not shown).

As best shown in Fig. 6, the tubes 73 are in communication at their inlet ends 76 to receive air from a blower M and at their opposite ends are in communication with a heated-air collecting chamber 77 into which is connected the preheated air supply line 63 already mentioned and which supplies air to the aspirating means 52. The blower M is motor driven and, as shown diagrammatically in Fig. 6, provides the motive power for moving the air through line 63. Thus, for maximum heat efficiency of the apparatus the amount of heat in the preheater exhaust gases, in excess of the maximum required to move them efficiently up the exhaust stack, will be extracted for use in preheating air in line 63.

A cooler 78 is mounted atop the cooling chamber C and has an inlet 79 and an outlet 81 communicating, respectively, with forward and rearward zones of the cooling chamber. A blower, generally designated 82, is provided in the cooler outlet 81 and is effective to draw gases of the cooling chamber atmosphere into the inlet 79, cool them, and if desired, dehumidify and desulphurize them, and direct them back into the cooling chamber through the outlet 81. Thus, it will be seen that the flow of cooled gas in the cooling chamber C is countercurrent to the flow of the strip 24 which will facilitate a gradual temperature reduction of the strip as it proceeds through this chamber. While only one outlet 81 is shown connected into the cooling chamber C, it will be preferred in some instances to provide a number of these outlets spaced at intervals along the cooling chamber to speed up the rate of cooling, where an increased rate of cooling is desired over that obtainable with the single outlet shown.

Another important part of the present invention resides in the internally cooled roll which I have provided for use with this apparatus and which is best shown in Figs. 2 and 4. In this instance, the roll is made up of a cylindrical or tubular section 83 joined as by welding at 84 to the journal members 86 and 87 at the ends thereof, the latter members being journaled within bearing members 88 and 89, respectively, which are secured to the opposite side walls of the apparatus. The journal member 87 is formed with a keyway 91 having key 92 engaging the sprocket

34 and is further provided with a bore or axial passage 93 within which is inserted a stationary spray tube 94 connected by piping 96 to a cooling water inlet. The portion of the pipe 94 within the journal member 87 constitutes the cooling water inlet and the annular space 95 between the bore 93 and the tube 94 constitutes the cooling water outlet. This outlet is restricted, by making it with a cross-section as small as can be employed and still carry away all the water needed, in order that the level of water in the roll be maintained as high as possible for the maximum cooling effect. Furthermore, to maintain the water level, additional outlet-restricting means in the form of the baffle 100 is provided. This baffle, being attached to the outer tube portion 83 as by welding at 101a, is provided with an opening 101b to receive the spray tube, and has a number of peripheral openings 101c to permit the restricted outlet flow of the cooling water. A valve 97, diagrammatically shown in Fig. 4, controls the amount of cooling water admitted to the inside of the roll. An individual valve 97 may be provided for each roll or one valve may control the cooling water in a number of rolls, depending on the requirements of a particular installation. A stationary funnel or cooling member 98 is disclosed below the outlet end member 87 to collect the heated water discharged from the roll and divert it to the outlet pipe 99.

An important feature of the roll cooling means disclosed resides in the upwardly disposed spray openings 101 which are formed along the length of the spray tube 94. Conventional internally cooled rolls have not been provided with upwardly directed sprays of this nature but instead have merely passed water through, usually in one end and out the other and as long as the roll was rotating, it remained cooled in a more or less uniform manner. However, as soon as the roll stopped, there was always a space at the top, either due to air collected in that position or due to vapor formed at the top, which caused the upper portion of the roll to heat at a much greater rate than the bottom portion in contact with the water. This uneven heating caused buckling beyond the proportional limit of the material in the roll and thenceforth, the roll would wobble in an eccentric manner causing the strip to take on a series of waves as it was moved from one roll to the next. The cooling means illustrated in Fig. 2 obviates this difficulty for, even when the roll is stopped for long periods of time, the upper portion remains just as cool as the lower portion due to the upwardly directed sprays through openings 101. A still further refinement of this invention is illustrated in Fig. 2a where it will be seen that the openings 101 are disposed, not only upward as previously explained, but upward in a tangential, non-radial manner. With this arrangement, the water sprays approaching the wall of the tubular member 83 in a more or less tangential manner cause the water therein to swirl in one direction (clockwise in Fig. 2a) around the inside of the roll thereby increasing the heat transfer and minimizing the volume of cooling water required.

Another important feature of the present invention, which greatly reduces heat loss from the apparatus to the cold rolls, is shown in Fig. 2a which illustrates a shielding member 102 made of ceramic or other heat insulating or heat reflecting material and formed with a roll-receiving trough 103. The shielding member surrounds, in spaced relation, a substantial part of

the roll, all except the upper portion which supports the strip 24. It minimizes heat transfer from the apparatus to the rolls by both conduction and radiation, especially the latter. In one particular installation, for example, use of a ceramic shield of the kind illustrated has reduced the heat loss to each roll by more than one-half without in any way impairing the strip-supporting function of the rolls.

I have found that the heat loss from the bottom half of the roll is, for all practical purposes, insignificant and from this I estimate that the heat loss to the roller taken as a whole is less than half the heat loss to conventional water-cooled rollers which are not so shielded.

By the use of my internally cooled roll, together with the heat shield described, I can dispense completely with the expensive alloy rolls previously considered essential for high temperature processes of this nature and can use rollers of ordinary steel throughout. It will be generally desirable to use the internally cooled rollers in both the heating and cooling chambers as well as for the elevated temperature portions of the preheating chamber. The entering rolls in the preheating chamber, however, may be made of alloy steel without the internal cooling feature, since the strip will be up to heat at this location and there is no problem of oxide accumulation on the rolls which would scratch the strip.

In normalizing, for example, cold rolled strip in the apparatus described above, fuel gas in admixture with air under pressure is delivered to the burners 47 in the main heating chamber B and ignited and the relative proportions of air and gas are so adjusted that only partial combustion of the fuel gas results. I desire to maintain an abnormally rich, reducing mixture of partially burned gases in the main heating chamber to prevent oxidation of the strip or other metal passing therethrough. I contemplate maintaining a rich gas mixture in which anywhere from 15% to 50% excess gas is used.

In order to utilize this unburned fuel gas, I deliver air through the jet members 54 of the aspirating means 52 which is effective to induce a portion of the rich gas in the heating chamber into the low pressure chamber 56 and thence into the preheating chamber A for additional combustion. Proper regulation of the valves 64 and 67 is made so as to control the heating effect in the preheating chamber. Some of the rich gas will pass through the strip opening 20 in separating wall 46 and this will be taken into account in adjusting the valves 64 and 67 to provide sufficient air to substantially completely burn it. While it is my desire to burn the gas in the preheating chamber as completely as possible, I prefer that the atmosphere therein be maintained slightly on the reducing side so as to prevent the oxidation of the strip especially the portion thereof near the rear or hottest end.

As the strip moves out of the chamber B into and through the chamber C, it is cooled by gases circulated through the cooler 78 and the blower 82. I contemplate, where it seems desirable, to operate the cooler at a low enough temperature to substantially dehydrate the gases; and furthermore, where it seems desirable, I contemplate washing the gases in a scrubber associated with the cooler, or otherwise suitably treating them, to desulphurize them.

The strip passing into the cooling chamber will be at sufficiently high temperature to oxidize readily in the presence of air. Consequently,

I contemplate maintaining the cooling chamber C at a pressure sufficiently lower than the heating chamber B to cause a portion of the rich heating chamber gases to flow through the opening 25. The gases in the cooling chamber eventually will be dissipated out of the end portion 31 but such loss will be constantly made up by inflow through the opening 25.

Thus, it will be seen that the partially burned gas in chamber B is diverted in two directions: (a) the major portion is aspirated into the preheating chamber for a more complete burning; and (b) the remainder is caused to flow into the cooling chamber to maintain a special atmosphere therein.

In one method of normalizing strip with my apparatus, for example, I regulate the supply of fuel gases and the speed with which such strip is fed through the apparatus so it attains a temperature of between 1300° F. when it reaches the bridge wall 46. After movement into the main heating chamber B, this temperature is quickly raised to around 1700° F. (preferably 1650° F. to 1800° F. and with the water-cooled, shielded rolls

I have disclosed may be operated at any desired temperature even as high as 2200° F.) and remains at about that point during the remainder of the travel through the chamber B, which therefore functions not only to bring the metal

to the desired maximum temperature but as a soaking chamber in which such temperature is maintained until the proper action is had upon the metal. During the passage of the strip through the cooling chamber C cooling at first is relatively slow until the strip progresses to a point where it is directly in line with the cold air emitting from the blower outlet pipe 81. From then on, the temperature drop is more rapid and the strip is preferably brought to 800° F. or less

at the point of discharge from the cooling chamber. This I term for convenience a non-oxidizing temperature because such a strip is not susceptible to quick oxidation or tarnishing under normal conditions after that temperature is reached.

I can also utilize this apparatus for annealing strip or metal sheets, in which operation the metal is brought to a temperature of around 800° in passing through the chamber A, quickly raised to 1350° F. after entrance into the chamber B, and is maintained at that temperature during the balance of their travel through B. Similarly to the normalizing procedure described, the strip is lowered to a temperature of 800° F. or less during passage through the cooling chamber C.

In the apparatus described, I am able efficiently and economically to obtain the desired heat treatment of the strip or other metal by direct application of fuel gas mixture in a continuous operation and in such a manner as to substantially obviate the formation of scale or oxide on the metal, and at the same time, contribute to the economy of operation by salvaging the unburned fuel for direct preheating use and for the maintenance of a reducing atmosphere in the cooling chamber.

It will be apparent that the specific method and apparatus described hereinabove is susceptible of variation and modification, and I do not wish to be restricted to such disclosure except as the claims, properly interpreted in view of the prior art, must be so limited.

I claim:

1. Apparatus for thermally treating material comprising a structure having means to support and move such material through a series of

chambers including preheating, heating, and cooling chambers, said heating chamber having means to generate and supply partially burned fuel gases thereto, means for conducting a portion of the partially burned fuel gases from the heating chamber to the preheating chamber and burning the gases to a more complete degree for directly preheating the material in the preheating chamber, and means for conducting a portion of the partially burned fuel gases from the heating chamber to the cooling chamber to maintain a special atmosphere about said material in said cooling chamber.

2. Apparatus for thermally treating material comprising a structure having means to support and move such material through a series of chambers including preheating, heating and cooling chambers, said heating chamber having means to generate and supply partially burned fuel gases thereto to provide a rich atmosphere therein, burner means associated with said preheating chamber adapted to directly preheat the material therewithin, means for conducting a portion of the partially burned gases from the heating chamber to said burner means and means for supplying an additional fuel component to the gases passing through said burner means for burning said gases to a more complete degree in the preheating chamber to directly preheat the material therewith, heat transfer means associated with a gas discharge outlet of said preheating chamber for transferring heat from the gases burned therewithin to the supply of said additional fuel component before it enters said burner means, means for conducting a portion of the partially burned gases from the heating chamber to the cooling chamber and means associated with the cooling chamber for subjecting the last-mentioned portion of gases to a special treatment to provide a special atmosphere for the material in the cooling chamber.

3. Apparatus for thermally treating material comprising a structure having means to support and move such material through preheating and heating chambers, said heating chamber having means for generating and supplying rich partially burned fuel gas mixture thereto, and Venturi means for transferring a portion of said rich mixture to the preheating chamber and mixing it with an additional fuel component to burn said portion to a more complete degree, said Venturi means comprising a pressure regain tube and a

jet member spaced therefrom by a low pressure space and positioned to discharge into said tube, said low pressure space being in communication with said heating chamber, said tube being in communication with said preheating chamber, and means for placing said jet in communication with a source of said additional fuel component.

4. Apparatus for thermally treating material comprising a structure having means to support and move such material through preheating and heating chambers, said heating chamber having means for generating and supplying a rich partially burned fuel gas mixture thereto, and means for aspirating a portion of the said rich mixture to the preheating chamber and mixing it with an additional fuel component to burn the aspirated portion more completely, said aspirating means comprising a pressure regain tube and a jet member spaced therefrom by a low pressure space and positioned to discharge into said tube, said low pressure space being in communication with said heating chamber, said tube being in communication with said preheating chamber, said jet member having a plurality of discharge openings each disposed to discharge into said tube, conduit means for placing each of said discharge openings in communication with a source of said additional fuel component, and means for controlling the flow of said component through at least one of said discharge openings independently of the flow through the rest.
